ATTORNEY.

UNITED STATES PATENT OFFICE.

GRACE HUNTINGTON BUCKLAND, OF FREMONT, OHIO.

DESIGN FOR FABRIC.

SPECIFICATION forming part of Design No. 35,351, dated November 26, 1901.

Application filed May 3, 1901. Serial No. 58,667. Term of patent 3½ years.

To all whom it may concern:

Be it known that I, GRACE HUNTINGTON BUCKLAND, a citizen of the United States, and a resident of the city of Fremont, in the county of Sandusky and State of Ohio, have invented and produced a new and original Design for Fabrics, of which the following is a specification, reference being had to the accompanying drawing, forming a part hereof.

10 This design relates to the ornamentation of cotton, silk, woolen, paper, celluloid, and other fabrics.

I have shown a plan view of my design.

As shown in the drawing, the interior figure or portion relates to the seal of the State of Ohio—namely, a shield bearing the coat of arms of the State of Ohio—to wit., a sun rising behind mountains. In the midground are trees and in the foreground sheaves of 20 wheat. Just below this shield is a scroll.

This shield is surrounded by a wreath composed of the leaves, flowers, and the fruit of the tree known as the "horse-chestnut" (*Aesculus*) of the United States, and more particularly as the *Aesculus glabra*, (Ohio 25 buckeye.) Some of the fruit or nuts are shown stripped of the bur or outer shell. At other places the burs or shells are shown.

Having described my invention, what I claim as new and of my invention, and desire 30 to secure by Letters Patent, is—

The design for a fabric herein shown and described.

In testimony whereof I have signed my name to this specification in the presence of 35 two subscribing witnesses.

GRACE HUNTINGTON BUCKLAND.

Attest:

C. B. CARR,
E. L. BOGUE.
